UNITED STATES PATENT OFFICE.

ELBRIDGE R. HOLMES, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

THREAD CUTTER FOR WEFT-REPLENISHING LOOMS.

Application filed June 18, 1925. Serial No. 38,067.

This invention relates to a thread cutter designed for use in a weft replenishing loom. In such looms, the bobbin is commonly ejected from the shuttle just prior to complete exhaustion of the weft thereon and it is necessary to sever the weft thread so that the ejected bobbin may draw the weft end entirely out of the shuttle eye, thus permitting accurate threading of the weft on the new bobbin and preventing the thread on the ejected bobbin from being drawn into the cloth.

It has been customary to cut the weft thread between the selvage and the shuttle box after the flight of the shuttle is completed but it has been found that the weft end sometimes becomes caught between the shuttle and the wall of the shuttle box and cannot be drawn clear of the shuttle eye.

It is the object of my invention to provide a construction by which the weft thread will be grasped and severed while the shuttle is in flight and before the shuttle enters the shuttle box.

Another object is to provide a thread cutter which is normally held in inoperative position but which is moved to operative position upon indication of weft exhaustion and which becomes effective to cut the weft during the next succeeding flight of the shuttle.

A further object is to provide a thread cutter which is released for cutting action by the shuttle as the shuttle passes the thread cutter, said cutter having been previously moved to operative position.

My invention further relates to arrangements and combinations of parts which will be hereinafter described and more particularly pointed out in the appended claims.

A preferred form of the invention is shown in the drawings, in which

Fig. 1 is a plan view of portions of a loom to which my improved thread cutter has been applied;

Fig. 2 is a front elevation of the parts shown in Fig. 1, with parts of the thread cutter shown in section along the line 2—2 in Fig. 1;

Figs. 3, 4 and 5 are sectional side elevations of my improved thread cutter and show successive operative positions thereof;

Figs. 6 and 7 are sectional plan views of

the thread cutter, taken along the line 6—6 in Fig. 3 and 7—7 in Fig. 5 respectively;

55

Fig. 8 is a side elevation of the cutting jaws in open position;

Fig. 9 shows the same parts in closed position;

Fig. 10 is a side elevation of the jaw-opening cam;

Fig. 11 is an end view of a shuttle designed for use with my improved thread cutter; and

Fig. 12 is a sectional view of the cutting jaws.

Referring to the drawings, I have shown portions of a loom including a breast beam 20, a thread cutting temple 21, a lay 22, a loom side 23 and a magazine frame 24.

70

A rock shaft 25 is pivotally mounted in the upper part of the magazine frame 24 and is provided with an arm 26 which is moved from the dotted line position in Fig. 2 to the full line position in said figure upon indication of transfer. All of the parts thus far described are of the usual construction and form no part of my present invention which relates more particularly to an improved thread cutter for use in connection with the several parts of the loom above set forth.

75

My improved thread cutter comprises a stand 30 formed with base and cover portions and mounted in fixed position upon the breast beam 20. A cutter slide 33 and a cam slide 34 are slidably mounted in the stand 30 for movement toward and from the lay 22. A spring 35 (Fig. 3) is mounted upon a rod 36 threaded into the cover of the stand 30 and the rear end of the spring 35 engages a bracket 37 secured to the top face of the cutter slide 33. In the rearmost position of the slide 33, as indicated in Fig. 4, the bracket 37 engages a shoulder on the threaded rod 36, by adjustment of which the rearward position of the slide may be adjusted.

90

A stud 38 (Fig. 6) is mounted in the slide 33 and extends through a slot 39 in the slide 34 and also through a slot 40 in the side of the stand 30. The outer end of the stud 38 is normally engaged by a lever 41 (Fig. 2) pivoted to the loom side at 43 and connected by a link 44 to the arm 26 previously described.

100

105

The lever 41 is normally in the lowered or dotted line position shown in Fig. 2 and engages the stud 38 as shown in Figs. 3 and 6. Upon indication of transfer, however, the lever 41 is raised by the usual movement of the shaft 25, releasing the stud 38 and permitting the slide 33 to move rearward from the position shown in Fig. 3 to that shown in Fig. 4, thus presenting the thread cutter in position for use.

The slide 33 is also provided with a second stud 46 (Figs. 6 and 7) projecting into a slot 48 formed in the cam slide 34. The slide 34 is provided with an offset projection 49 which engages the front end of the stand 30 and limits rearward movement of the cam slide. A light coil spring 50 is seated in the slot 48 between the rear end of the slot and the stud 46 and tends to move the slide 34 rearward relative to the slide 33 to the position indicated in Figs. 3 and 6.

When the slide 33 is released to move to operative position, the slide 34 moves in the same direction until its projection 49 engages the front end of the stand 30 and thereafter the slide 33 moves rearward relatively to the slide 34, as the spring 50 is strong enough to overcome and compress the spring 50.

The cutter slide 33 is provided at its rear end with an upper cutting jaw 52 (Figs. 8 and 9) on an arm 53 which is a part of or secured to said slide and with a lower cutting jaw 54 mounted on an arm 55 pivoted at 56 to said slide. The slide 33 also has a depending projection 57 to which a contact lever 58 is pivoted at 59. The lever 58 is weighted at its forward end and normally occupies the position indicated in Fig. 3. The rear end of the lever 58 is notched to receive an actuating member or dagger 60 carried by the lay 22.

A wire plunger 61 (Fig. 9) is pivoted at 62 to the movable cutter arm 55 and extends upward through the fixed arm 53 which supports the cutting jaw 52. A spring 63 is positioned between the fixed arm 53 and a head 64 on the rod 61, thus acting to yieldingly move the cutters from the open position shown in Fig. 8 to the closed position shown in Fig. 9.

A second rod 61^a is also pivoted at 62 and extends downward therefrom. The rod 61^a has a shoulder 65 and an offset end portion 66 which extends loosely through an opening 67 in the contact lever 58. When the cutting jaws are opened, as indicated in Fig. 8, by mechanism to be described, the shoulder 65 engages the lever 58 and moves the lever from the position shown in Fig. 3 to the position shown in Fig. 4 in which position it will be engaged by the dagger 60.

A cam plate 70 (Fig. 10) is pivoted on a vertical stud 71 mounted in the rear end

of the cam slide 34. A light coil spring 72 is mounted on the stud 71 and its ends engage the plate 70 and the slide 34, normally maintaining the cam plate 70 in the operative position shown in Fig. 6.

The cam plate 70 extends rearward between studs 73 and 74 on the fixed and movable cutting jaws, but in the normal position of the parts indicated in Figs. 3 and 6, the studs are adjacent the narrow portion 75 of the cam plate which permits the jaws to remain in closed position. When the parts are released upon indication of transfer and the thread cutter moves rearward, the slide 33 moves rearward further than the slide 34, as previously described, thus causing the stud 74 on the lower cutting jaw 54 to move rearward along the cam face 76 of the plate 70, thus opening the cutting jaws as indicated in Fig. 4. The stud 73 on the upper jaw 52 acts as a guide for the cam plate 70 during such operation thereof. When the cutter slide 33 is in its extreme rearward position relative to the cam slide 34, the stud 74 is received behind a spur or projection 77 of the cam plate, which holds the jaws open as the slides are moved forward by engagement of the lever 58 by the dagger 60.

By the mechanism thus far described, the thread cutter is released and allowed to move rearward to meet the advancing lay, at the same time opening the cutting jaws and latching them in open position. As the dagger 60 engages the lever 58, direct pressure is applied to the depending portion 57 of the slide 33 and the cutter is moved forward in definite relation to the lay.

The shuttle S is provided with a projection 80 (Figs. 1 and 11) having a cam face 105 to engage the rear end of the cam plate 70 as the shuttle approaches the adjacent shuttle box. This projection 80 is grooved or recessed at 81 (Fig. 11) to receive the weft W and to assist in presenting the same between the cutting jaws. As the projection 80 of the shuttle reaches the thread cutter, the projection passes between the open jaws and strikes the end of the cam plate 70, swinging the same away from the cutting jaws as clearly indicated in Fig. 7. This releases the stud 74 and permits the jaws to close, severing the weft thread as indicated in Fig. 1. The arms 53 and 55 which support the cutting jaws have serrated surfaces 53^a and 55^a (Fig. 12) which grasp the weft end extending from the selvage and hold it for the temple thread cutter.

The shuttle with its very short weft end thereafter enters the shuttle box and the bobbin is transferred, drawing the short weft end easily from the shuttle eye. As the thread cutter is thereafter pushed forward by the dagger 60 to its extreme forward position, the lever 41 is again lowered to en-

gage the stud 38 and thus retain the thread cutter in normal or forward position. As soon as the lay moves rearward and disengages the dagger 60 from the lever 58, the counterweight of the lever causes it to swing to the position shown in Fig. 3, in which it is out of the path of the dagger 60. The parts remain in this position until another indication of transfer.

10 I have thus provided a thread cutter which is effective to grasp and cut the weft end upon indication of transfer while the shuttle is in flight and before the shuttle enters the shuttle box. This I believe to be novel 15 and very important, as it greatly reduces the chances of subsequent misthreading. My invention makes it easy for an ejected bobbin to draw after it the short weft end left beyond the shuttle eye. This is particularly 20 important when the amount of yarn left on the bobbin is very small, as any substantial resistance to free passage of the weft then causes the bobbin to unwind and leave the thread in the shuttle where it is sure to be 25 carried into the cloth and produce a serious defect.

Having thus described my invention and the advantages thereof, I do not wish to be limited to the details herein disclosed, otherwise than as set forth in the claims, but what 30 I claim is:—

1. In a loom, a shuttle, a stand, a cutter slide and a cam slide mounted in said stand, a fixed and a movable cutting jaw on said 35 cutter slide, a cam plate pivoted on said cam slide to swing in a horizontal plane, said cam plate operating on rearward movement of said slides to open and hold said cutting jaws, and said shuttle thereafter 40 engaging said cam plate and swinging said plate sidewise to release said jaws.

2. In a loom having a shuttle and a shuttle box, in combination, a stand, a cutter slide and a cam slide mounted in said stand, a fixed and a movable cutting jaw on said 45 cutter slide, a cam plate pivoted on said cam slide to swing in a horizontal plane, said cam plate operating on rearward movement of said slides to open and hold said cutting jaws, and said shuttle having a projection 50 effective to engage said cam plate as the shuttle approaches the shuttle box and swinging said plate side wise to release said jaws.

3. A construction as set forth in claim 2, in which the projection on the shuttle is grooved longitudinally to receive the weft and to position the weft between the cutting jaws.

4. In a loom, a lay, a shuttle, a stand, a cutter slide and a cam slide mounted in said stand, a fixed and a movable cutting jaw on said cutter slide, and said cam slide having a cam portion at its rear end effective to open said cutting jaws upon rearward move-

ment of said cutter slide relative to said cam slide.

5. A construction as set forth in claim 4, in which the lay is provided with a projection and in which a contact member is mounted on said cutter slide and is movable by opening movement of said jaws to position for engagement by said projection, whereby said cutter slide is moved forward to normally inoperative position. 75

6. A construction as set forth in claim 4, in which the lay is provided with a projection and in which a contact member is mounted on said cutter slide and is movable by opening movement of said jaws to position for engagement by said projection, 80 whereby said cutter slide is moved forward to normally inoperative position, and in which a lost motion connection permits the cutting jaws to close while said contact member and projection remain engaged. 85

7. A construction as set forth in claim 4, in which the lay is provided with a projection and in which a contact member is mounted on said cutter slide and is movable by opening movement of said jaws to position for engagement by said projection, whereby said cutter slide is moved forward to normally inoperative position, and in which said contact member is counterweighted to return to a position out of the path of 90 said projection, when released thereby. 95

8. In a loom, a lay, a thread cutter adjacent the selvage of the cloth, means to hold 100 said thread cutter normally in forward inoperative position, means to return said cutter to such forward position after a single operation thereof and to cause said holding means to again become operative, and a normally inoperative connection between said lay and said thread cutter, which connection including an engaging member mounted on 105 and movable with the thread cutter, and also movable relative thereto to engage and to inoperative positions, said connection being rendered operative by rearward movement 110 of said thread cutter and being thereafter rendered again inoperative after a single forward movement of said thread cutter thereby. 115

9. In a loom, a shuttle, a shuttle box, a weft replenishing mechanism, and means to cut the weft upon indication of weft exhaustion and before the running shuttle enters the shuttle box for weft replenishment, 120 said cutting means being supported externally to and separated from said shuttle, and being effective to cut the weft outside of the shuttle.

10. In a loom, a shuttle, a shuttle box, a thread cutter mounted adjacent the cloth selvage, and means effective to actuate said thread cutter to cut the thread outside the shuttle before the shuttle enters a substantial distance into the shuttle box. 125 130

11. In a loom, a shuttle, a shuttle box, a thread cutter mounted adjacent the cloth selvage, and means effective to actuate said thread cutter to cut the thread outside the shuttle while the shuttle is in flight toward said box.
12. In a loom, a shuttle, a shuttle box, and a thread cutter mounted outside of and separate from said shuttle, said shuttle engaging a portion of said thread cutter and rendering said thread cutter operative to cut the thread outside the shuttle as said shuttle approaches the shuttle box.
13. In a loom, a thread cutting mechanism comprising a slide, means to hold said slide normally in forward inoperative position, means to move said slide rearward upon indication of transfer, a pair of cutting jaws on said slide, means to open said jaws as said slide moves rearward, and means to close said jaws, said closing means being controlled by the active shuttle while said shuttle is in flight.
14. In a loom, a thread cutting mechanism comprising a slide, means to hold said slide normally in forward inoperative position, means to move said slide rearward upon indication of transfer, a pair of cutting jaws on said slide, means to open said jaws as said slide moves rearward, and means to hold said jaws open, said holding means being displaced from holding position by the running shuttle as it approaches the shuttle box after weft replenishment.
15. In a loom, a lay, a shuttle, a thread cutter movable forward and rearward in said loom, cutting jaws for said thread cutter, means to open said jaws as the cutter moves rearward, means to hold said jaws in definite spaced relation to the lay during forward movement thereof, and a projection on the shuttle effective to engage and release said thread cutter for cutting action while said thread cutter is thus positioned.
16. In a loom, a lay, a shuttle, a thread cutter movable forward and rearward in said loom, cutting jaws for said thread cutter, means to open said jaws as the cutter moves rearward, means to hold said jaws in definite spaced relation to the lay during forward movement thereof, and a projection on the shuttle effective to engage and release said thread cutter for cutting action while said thread cutter is thus positioned, thereby severing the thread and grasping the severed end.

In testimony whereof I have hereunto affixed my signature.

ELBRIDGE R. HOLMES.
